UNITED STATES PATENT OFFICE.

FRANK L. MOORE, OF TRUMANSBURG, NEW YORK.

PISTON-RING COMPRESSOR.

Application filed December 8, 1920, Serial No. 429,116. Renewed September 26, 1923.

To all whom it may concern:

Be it known that I, FRANK L. MOORE, a citizen of the United States of America, residing at Trumansburg, in the county of 5 Tompkins and State of New York, have invented certain new and useful Improvements in Piston-Ring Compressors, of which the following is a specification, reference being had therein to the accompanying drawing.

My invention relates to tools for handling parts of engines, and has special reference to that class of devices used for setting and removing piston rings, and for inserting 15 and removing the pistons in and from cylinders.

My invention has for its object the improvement of such tools. I attain this object by employing a sleeve or band of peculiar form applicable to pistons of various diameters, which is the first feature of improvement; also capable of convenient control from the crank case end of cylinders, and other locations usually found very inconvenient with ordinary tools, which is the second feature of improvement; also having stops adapted to fit any piston ring within its range, which is the third feature of improvement; and being adjustable with 20 out specific spaced steps, ensuring equal action for all sizes, which is the fourth feature of improvement. Other features, such as the applicability of this tool to the removal of rings from the pistons, etc., will 25 sufficiently appear from the detailed description.

My invention is illustrated in the accompanying drawings in which:—

Fig. 1 is a side view of the device applied 40 to a piston;

Fig. 2 is a section on the line 2—2 of Fig. 1; and

Fig. 3 is a longitudinal section taken 45 through the plane of the axes of the clamping band and tightening rod with the rod shown in full.

Referring to the drawings in detail, the device, which takes the general form of a circular clamp, comprises a main clamping band 1 having its ends overlapped as indicated at 2 and held together by an auxiliary band or tongue 3, fixed to the main band at 4, and a holder 5 fixed to the main band at 6. The auxiliary or tightening band 3 50 connects with the holder 5 through a split winding rod 7 nested in the cylindrical

holder 5, the band 3 entering the holder through the opening 8 and engaging with the winding rod through means of a slot 9. By extending the slot through the end of 60 the rod as indicated the two sides of the slotted portion are rendered capable of being brought together to bind the end of the tightening band therebetween under the clamping action of the band on the rod. 65

As a locking means for the winding rod I use a thumb set-screw 10 passed through a threaded opening 11 in the wall of the holder 5 into engagement with the winding rod at a point above the slot. The winding 70 rod 7 extends from the holder 5 to form an elongated handle 12 by which the device may be controlled from a point removed according to the amount of extension of the rod. 75

A radially extending lug 13 is carried by the main band substantially diametrically opposite the holder 5, and which together with the bottom of the holder 5 forms a pair of stops adapted to fit any ring within the 80 range of the device. The upper edge of the main band 1 is flared as indicated at 14 while the lower edge is curved inwardly as indicated at 15 for a purpose which will be brought out in the description of operation. 85

In the operation of inserting a piston in the cylinder of an engine, say downwardly from the top of the cylinder, the clamp is placed on the piston head 16, as indicated in Fig. 1 so as to surround the lower piston 90 ring but with the lower edge of the clamp slightly above the bottom of the piston. The projecting lower portion of the piston 16 is then inserted in the cylinder after which the whole piston head is pushed down 95 into the cylinder through the ring formed by the main band 1, the flared edge 14 and inwardly curved edge 15 acting to gradually compress the piston rings into the clamp and to give them a final compression 100 as they leave the bottom of the clamp.

In inserting a piston from the lower or crank case end of the cylinder, the operation is the same except that the clamp is initially placed over the upper rings with 105 the handle extending downwardly.

In installing or removing piston rings, the ring is drawn over the lower end of the clamp on the outside of the clamp up against the lug 13 and the bottom of the 110 holder 5, as indicated in dotted lines at 17 in Fig. 3, which enables the ring to be

moved over the piston without encountering other rings or engaging the wrong groove.

It is to be noted that the holder 5 and winding rod 7 with its controlling handle 12 constitute actuating means not limited to any fixed adjustment or adjustments but acting continuously upon the auxiliary or drawing band 3 to clamp any size piston within the limits of its range of operation.

10. What I claim is:

1. A clamp for piston rings comprising an open ring band for clamping, a flexible drawing band or strap having one end attached to the clamping band at one side of its opening and an actuating device for the drawing band secured to the clamping band on the other side of the opening and receiving and drawing continuously upon the free end of the drawing band.
15. 2. The clamp claimed in claim 1 having a handle for the actuating means with means extending parallel to the axis of the clamping band and beyond the end of the entire tool, for locking the same when set.
20. 3. The clamp claimed in claim 1 having fixed stops at separated points on the clamping band, adapted to engage the edges of rings of varying diameters.
25. 4. The clamp claimed in claim 1 having the actuating means acting continuously upon the drawing band to clamp any size cylinder within its range without specific

spaced steps, and locking means operable at will at any point in the clamping operation.

5. The combination tool described herein comprising a flexible clamping band, a flexible drawing band attached to one side of the clamping band intermediate of its ends, an actuating device for the drawing band secured to one end of the clamping band and receiving and drawing upon the end of the drawing band, said clamping band being flared around one edge to permit ready insertion of piston rings therein.

6. The tool claimed in claim 5 having one edge of the clamping band outwardly bevelled or flared and the other edge inwardly turned, with stops on the band above said edge, whereby the piston rings are gradually compressed as the piston is forced down through the clamp, and finally compressed as they leave the bottom of the clamp, eliminating friction between the piston and the band, and whereby also the same tool may be used to remove a ring by drawing the ring over the outside of the band against the stops thereon, the ring and band being then slid able along the piston and removable therefrom if desired.

In testimony whereof I affix my signature.
FRANK L. MOORE.
